(57) **CLAIM**

The ornamental design for a spout, as shown and described.

DESCRIPTION

In a preferred embodiment, the nature of this product is as a plumbing fixture in the form of a spout primary useful for washing various items, particularly items in kitchens.

FIG. 1 is a right, top, front perspective view of a spout embodying my new design;

FIG. 2 is a right side elevational view thereof, the left side being a mirror image of the right side shown;

FIG. 3 is a front elevational view thereof;

FIG. 4 is a rear elevational view thereof;

FIG. 5 is a top plan view thereof;

FIG. 6 is a bottom plan view thereof;

FIG. 7 is a right, top, front perspective view of a faucet according to another embodiment of my new design;

FIG. 8 is a right side elevational view thereof, the left side being a mirror image of the right side shown;

FIG. 9 is a front elevational view thereof;

FIG. 10 is a rear elevational view thereof;

FIG. 11 is a top plan view thereof; and,

FIG. 12 is a bottom plan view thereof.

The broken line representations of internal spout structure in FIGS. 6 and 12, and a lower escutcheon in FIGS. 7-12, are for the purpose of illustration only, and form no part of the claimed design.
